Primary Examiner — Eric Goodman*Assistant Examiner* — Daniel J Domino(74) *Attorney, Agent, or Firm* — Cooper & Dunham LLP(57) **CLAIM**

The ornamental design for a hose and connectors, as shown and described.

DESCRIPTION

FIG. 1 is a side view of a hose and connectors. The hose is shown with a symbolic break in its length. The appearance of any portion of the hose between the break lines forms no part of the claimed design;

FIG. 2 is a top view thereof; and,

FIG. 3 is a bottom view thereof.

The broken line showing is included for the purpose of illustrating portions of the article and forms no part of the claimed design.

1 Claim, 2 Drawing Sheets(56)
